OTHER PUBLICATIONS

Sylvania PAR 38 lamp, on sale by Osram Sylvania Inc. in the U.S. more than one year before Applicants' filing date herein (color photograph, 1 page).

(Continued)

Primary Examiner — Cathron Brooks*Assistant Examiner* — Kevin K Rudzinski(74) *Attorney, Agent, or Firm* — Edward S. Podszus(57) **CLAIM**

The ornamental design for a par lamp, as shown and described.

DESCRIPTION

FIG. 1 is a side elevation view of the new design for a par lamp, the other sides being the same; and,
FIG. 2 is a bottom plan view thereof.

The broken line disclosure is for environmental purposes only and does not form a part of the claimed design.
